US00D781430S

(12) **United States Design Patent** (10) **Patent No.:** **US D781,430 S**
(45) **Date of Patent:** **** Mar. 14, 2017**

(54) **POWER ASSIST SUIT**

(71) Applicant: **Panasonic Corporation**, Kadoma-shi, Osaka (JP)

(72) Inventors: **Makoto Konishi**, Osaka (JP); **Takuo Wariishi**, Osaka (JP); **Hiroki Tanabayashi**, Kyoto (JP); **Hiroshi Kanchiku**, Nara (JP); **Hiromichi Fujimoto**, Nara (JP)

(73) Assignee: **PANASONIC CORPORATION**, Osaka (JP)

(**) Term: **15 Years**

(21) Appl. No.: **29/545,365**

(22) Filed: **Nov. 12, 2015**

(30) **Foreign Application Priority Data**

May 18, 2015 (JP) 2015-010748

(51) **LOC (10) Cl.** **24-04**

(57) **CLAIM**

We claim the ornamental design for a power assist suit, as shown and described.

DESCRIPTION

FIG. 1 is a front and top perspective view of a power assist suit showing our new design;

FIG. 2 is a rear and top perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines in the drawings are included for the purpose of illustrating portions of the power assist suit and forms no part of the claimed design.

1 Claim, 8 Drawing Sheets
